UNITED STATES PATENT OFFICE.

ALBERT H. NELLER, OF FAIRFIELD, IOWA, ASSIGNOR TO THE LOUDEN MACHINERY COMPANY, OF FAIRFIELD, IOWA, A CORPORATION OF IOWA.

OVERHEAD CARRIER.

1,291,606.

Specification of Letters Patent. Patented Jan. 14, 1919.

Application filed August 31, 1918. Serial No. 252,235.

To all whom it may concern:

Be it known that I, ALBERT H. NELLER, a citizen of the United States, residing at Fairfield, in the county of Jefferson and State of Iowa, have invented certain new and useful Improvements in Overhead Carriers, of which the following is a specification.

My invention relates to improvements in overhead carriers, such as may be used in garages and other similar places and it consists of the construction and arrangement of the parts whereby the hoisting tackle which is attached to the carrier and preferably manually shifted to any point within specified limits, either laterally or longitudinally. Also, in the details of the construction and arrangements of the parts, as will be hereinafter described and more definitely defined in the claims.

In the accompanying drawings forming a part of this specification, Figure 1 is a perspective of an overhead carrier embodying the features of my invention. Fig. 2 is an enlarged vertical transverse section on line 2—2 of Fig. 1, looking in the direction of the arrow. Fig. 3 is the same on line 3—3 of Fig. 1. Figs. 4 and 5 are enlarged detail views which will be described later on.

Referring to the drawings, A represents the ceiling of a building which has supporting beams B located thereon. C represents timbers which are spaced apart and connected transversely to said beams, so as to be above the portion of the room in which the overhead carrier is to operate. To each of these timbers an overhead track D is hung by means of a series of hangers E which may be of any preferred construction. On these tracks carriers F are mounted so as to run past the hangers E from one end to the other of the respective tracks.

A third timber G disposed transversely to the timber C and tracks D is suspended to the carriers F as shown in the drawing by straps H connected at their upper ends to clevises I attached to the carrier frames so as to support the timber G in its transverse position below the tracks D. A third track J is suspended to the timber G by means of a series of hangers K which may be of a construction similar to that of the hangers E or of any suitable construction to support the track J so as to run past the

hangers K from one end of the track to the other.

A hoisting tackle (not shown) will be connected to the carrier L as indicated by the section of chain M so that articles to be handled may be raised and lowered and be supported in elevated position by the carrier L, as will be readily understood by those skilled in the art to which my invention pertains. It will also be readily understood that when the article is suspended to the carrier L it may be moved laterally by pushing the carrier L along the track J, and also longitudinally by pushing the carriers F along the tracks D. To facilitate this latter movement is the principal object of my invention and the means employed to accomplish this object are as follows.

A rotatable shaft N is mounted on the timber G so as to project beyond the upper edge of the timber. Sprocket wheels O are mounted on the projecting ends of the shaft and horizontally disposed leading chains P are passed through the respective sprocket wheels. The respective ends of the chains are secured to downwardly extending supports Q having their upper ends attached to the respective ends of the timbers C, and preferably supported thereon by braces R. One end of the shaft N is extended beyond the sprocket wheel on that end and a wheel carrying a hand chain T is mounted on this extended end of the shaft.

To move the carriers F along the tracks D in either direction, all that is necessary is for the operator to pull the hand chain in one direction or the other. This will cause the shaft N to rotate and the sprocket wheels O to travel along the chain P in the desired direction, thus carrying the timber G connected to the carriers E along the tracks D. By this means the track J with carriers L being attached to the timber G will be drawn longitudinally to any desired point within the limits of the tracks D.

An enlarged detail view of the sprocket wheel is shown in Fig. 2. The shaft N is preferably made of tubing and the sprocket wheels are secured to it so they will rotate with it. The links of the chain P are made so they will catch over and connect with the sprockets of the wheel in the usual manner, and in order to prevent the chain from slipping over a guard U is provided. This

guard is made so its central portion will straddle the sprocket wheel and is loosely mounted or pivoted on the shaft on each side of the sprocket as plainly shown in Fig. 5 4 which is an enlarged view of the part looking up from the under side, the chain being removed.

The guard U is preferably made in two parts joined together by a rivet V as shown 10 in Fig. 5, which is a transverse section on line 5—5 of Fig. 4. The under sides of the ends of the members forming the guard which is marked U' are curved and made rounding where they are joined together, 15 thus making smoothly rounded and slightly hollowed faces for the chain to slide under when the sprockets are being rotated and the chain is passing over them.

The guard being loosely mounted on the 20 shaft its ends will be free to tilt upward or downward as they may be drawn by the relative tightness or slackness of the ends of the chain on opposite sides of the sprocket. In this way the chains P being passed under 25 the ends U' of the guard will be effectually prevented from slipping over the sprocket and at the same time the pressure of the ends of the guard on the opposite ends of the chain will be always uniform.

30 Fig. 3 is a transverse vertical section of the timber G and track J, on the line 3—3 of Fig. 1, and shows the sprocket wheel O, chain wheel S and one of the track hangers K in the background. As shown in the 35 drawings the timber G is fitted on its upper edge with a horizontally disposed laterally projecting member W which served to strengthen it laterally and prevent it from buckling in carrying a heavy load. Material 40 other than wood may be used for the members C and G if preferred, and where the beams B are not used the member C may be connected to the ceiling A in any suitable manner.

45 In the drawings and description relating thereto, I have merely undertaken to typify my invention, and, therefore do not wish to be understood as intending to limit the same to the details shown and described. It will 50 be readily apparent that while the beams C and G are preferred as mediums from which the tracks or ways may be suspended, yet they may be omitted, and the parallel tracks or ways suspended direct from the structural timbers of the building and the transverse track directly from the parallel tracks or ways.

What I claim is—

1. In an overhead carrier, the combination 60 of an upper track, a carriage movable over the upper track, a lower track supported by said element at an angle to the upper track, a carrier on the lower track, a toothed wheel rotatably mounted adjacent the lower track and adapted to move therewith, means

for rotating the wheel, and a correspondingly formed co-acting feed-track fixedly mounted adjacent and parallel to the upper track.

2. In an overhead carrier, the combination 70 of a pair of parallel tracks, carriages mounted for movement thereover, suspension means for the carriages, a track disposed at an angle to and below the parallel tracks and supported by said suspension means of 75 the carriages, a carrier on the lower track, a rotatable shaft movable with and supported adjacent the lower track, means for operating the shaft, a toothed wheel carried by the shaft, and a correspondingly formed co-acting feed-track meshing with the toothed wheel and mounted adjacent and parallel to the parallel tracks.

3. In an overhead carrier, the combination 80 of a pair of parallel tracks, a pair of carriers mounted on and adapted to traverse said tracks, a supporting member connected near its ends to and supported by said carriers and disposed at an angle to the tracks, a track arranged parallel to and suspended 90 from said supporting member, a carrier mounted on the latter track, and a propelling means carried by the supporting-member.

4. In an overhead carrier, a pair of overhead tracks paralleling each other, a pair of carriers mounted on and adapted to traverse said tracks, a supporting-member connected to and suspended from said carriers and disposed at an angle thereto, a track suspended 100 from and paralleling the supporting-member, a carrier movable on said latter track, and means for moving said carriers on the parallel tracks.

5. In an overhead carrier, a pair of horizontally disposed supporting members attached to the ceiling of a building in parallel relation to each other, a trackway suspended in parallel relation to each of said members, a pair of carriers mounted on and adapted to traverse said tracks, a supporting member connected near its ends to said carriers and arranged to stand in transverse relation to the aforesaid pair of supporting members and the tracks connected thereto, a track suspended from said transverse supporting member in parallel relation thereto, a carrier mounted on and adapted to traverse said latter track and means to manually propel the aforesaid pair of carriers and to cause them to traverse the aforesaid trackways.

6. In an overhead carrier, a pair of horizontally disposed supporting members attached to the ceiling of a building in parallel relation to each other, a trackway suspended in parallel relation to each of said members, a pair of carriers mounted on and adapted to traverse said tracks, a supporting member connected near its ends to said carriers

and arranged to stand in transverse relation to the aforesaid pair of supporting members and the tracks connected thereto, a track suspended from said transverse supporting member in parallel relation thereto, a carrier mounted on and adapted to traverse said latter track, a pair of horizontally disposed chains supported at each end by the aforesaid parallel supporting members, 5 a rotatable shaft mounted on the transverse supporting member, a sprocket wheel on each end of the shaft and connected to said chain whereby the rotating of the shaft will cause the sprockets to transverse the chains 10 so that the pair of carriers will traverse the parallel tracks carrying with them the transverse supporting member and the track and carrier connected therewith, a chain wheel 45 on one end of the shaft, and an endless chain hung on the wheel, whereby an operator by pulling the chain in one direction or the other will rotate the shaft and cause the pair of carriers to traverse the parallel 50 tracks.

10 7. In an overhead carrier, a pair of horizontally disposed supporting members attached to the ceiling of a building in parallel relation to each other, a trackway suspended in parallel relation to each of said members, 15 a pair of carriers mounted on and adapted to traverse said tracks, a supporting member connected near its ends to said carriers and arranged to stand in transverse relation to the aforesaid pair of supporting 20 members and the tracks connected thereto, a track suspended from said transverse supporting member in parallel relation thereto, a carrier mounted on and adapted to traverse said latter track, a pair of horizontally 25 disposed chains supported at each end by the aforesaid parallel supporting members, a rotatable shaft mounted on the transverse supporting member, a sprocket wheel on each end of the shaft and connected to said 30 chain whereby the rotating of the shaft will 35 40

cause the sprockets to transverse the chains so that the pair of carriers will traverse the parallel tracks carrying with them the transverse supporting member and the track and carrier connected therewith, a chain wheel 45 on one end of the shaft, and an endless chain hung on the wheel, whereby an operator by pulling the chain in one direction or the other will rotate the shaft and cause the pair of carriers to traverse the parallel 50 tracks.

8. In a device of the character described, a pair of overhead tracks and carriers arranged in parallel relation to each other, a transverse member suspended near its ends 55 by said carriers, a track and carrier supported by said member, a rotatable shaft mounted in parallel relation on said transverse member and its ends projecting beyond the ends of said member, sprocket 60 wheels on said projecting ends, a pair of horizontally disposed chains laid in the path of the sprocket wheels and having their ends rigidly supported, whereby the rotation of the shaft will cause the sprockets to traverse the chains as and for the purpose set forth. 65

9. In a device of the character described, a rotatable shaft having sprocket wheels thereon, anchored chains placed in the path 70 of the sprockets, guards loosely mounted on the shaft so their central portions will straddle the sprockets and having concave convex ends to slide over the chain and prevent it from slipping off the sprockets.

Fairfield, Iowa, August 28, 1918.
